DRY STEAM SPRAYER

Jacob Schwartz, Brooklyn, N. Y.

Application March 26, 1935, Serial No. 13,108

17 Claims. (Cl. 299—149)

The purpose of this invention is to improve devices for spraying dry steam by making it possible to provide complete control over the steam at the nozzle and by the hand in which the 5 nozzle is held and also to provide a return adapted to take all condensation away from the control valve.

The invention is a steam valve having a live steam connection passing straight through the 10 upper part thereof with a condensation pocket extending downward therefrom and connected to a return so that condensation may pass directly into the return and also so that live steam may pass into the return as soon as the valve 15 is closed. A handle is provided by which the valve may be held by hand and the valve is also formed with a lever at one side which is positioned so that the valve may be opened and closed by the thumb of the hand by which it is 20 held.

Many other devices have been provided for this purpose but any of them do not provide a straight live-steam passage or a condensation pocket with a return connected in the pocket 25 and arranged so that the live steam may pass into the return when the valve is closed. One device, in particular, is divided into two chambers with a valve between the chambers but condensation may collect in the chamber beyond 30 the valve and this will be ejected with the spray as soon as the valve is opened. Other devices have been provided for draining off the condensation but in every instance it is possible for a small amount of condensation to collect in 35 the valve when the valve is closed and it is desired to provide a valve of this type which will only spray dry steam and which will not spray or "spit" water at any time during the operation thereof.

40 The object of the invention is, therefore, to provide a device for spraying dry steam in which all danger of condensation being sprayed therefrom is eliminated.

Another object is to provide a dry steam spraying device which has a tendency to dry steam 45 as the steam passes therethrough.

Another object is to provide a dry steam spraying device which is provided with a return connection to which all condensation may pass 50 and through which the steam may pass when the valve is closed so that continuous circulation of the steam is maintained with the valve opened or closed.

Another object is to provide a dry steam spraying device in which the full control of the 55

spray is at the point from which the steam is sprayed.

Another object is to provide a dry steam spraying device in which the amount of steam being sprayed may be regulated at the spray and this may be accomplished without danger of 5 condensation accumulating therein.

A further object is to provide a dry steam spraying device which may be instantly shut off at the point from which the spray is ejected. 10

And a still further object is to provide a dry steam spraying device having full control of the spray and in which all danger of condensation is eliminated which is of a simple and economical construction. 15

With these ends in view the invention embodies a valve body with live steam and return connections at one end, a nozzle at the other, a valve adjacent the nozzle and a lever adapted to operate the valve extending upward to a point 20 adjacent the end of a handle, by which it may be held.

Other features and advantages of the invention will appear from the following description taken in connection with the drawing, 25 wherein:

Figure 1 is a view showing a side elevation of the device with part broken away showing the return pipe connection.

Figure 2 is an end view looking toward the 30 nozzle or discharge end of the device.

Figure 3 is a plan view of the valve body with the lower part of the forward end of the handle shown in section and with parts omitted.

Figure 4 is a detail showing a sectional plan 35 through the valve.

In the drawing the device is shown as it may be made wherein numeral 1 indicates the valve body, numeral 2 the valve member, and numeral 3 a handle by which the device may be held. 40

The valve body 1 is of a rectangular shape with the base sloping toward one side, however, it will be understood that the shape or design of the body may be changed to accommodate different conditions or different methods of construction or different material of which the device may be made. In the design shown the valve body is made of a casting which is substantially hollow and in which numeral 4 indicates the chamber on the interior, numeral 5 50 the back, and numeral 6 a discharge nipple to which the nozzle 7 may be connected.

A live steam supply connection is provided by a nipple 8 which is threaded into a boss 9 at the upper corner of the back 5 and this con- 55

nection opens into the interior chamber 4. A return connection is provided in the lower corner of the valve body and this is formed by a nipple 10 which is threaded into a boss 11 and on the inner end of the nipple 10 is a smaller nipple or bushing 12 which is threaded into the nipple 10 and which extends into the chamber 4 to the point 13 so that all condensation accumulating in the lower part of the valve body 10 will pass directly into the return through the nipples 12 and 10. It will be understood, however, that the nipple or bushing may be omitted so that the condensation will enter the nipple 10 direct, however this connection may be formed 15 in any manner, or by any means.

The sides of the valve body are drawn together as shown at the point 14 in Figure 4 and this section of the valve body is provided with a boss 15 at one side and a corresponding boss 16 directly opposite and positioned on the other side. The nipple 6 extends outward from the opposite side of the bosses 15 and 16 and the nozzle 7, which is formed of a short piece of tubing in which the outer end is flattened and the inner end threaded into the nipple 6 as shown 25 in Figures 1 and 4.

An opening 17 is provided in the boss 15 and a bushing 18 is threaded into this opening as shown in Figure 4 with the valve member 2 slidably held in the bushing 18 and resiliently held 30 against a valve seat 19 by a spring 20. The opening 17 connects with the interior of the valve body 1 through a passage 21 and an opening 22 on the opposite side of the valve seat 19 connects with the interior of the nozzle 7 through a 35 passage 23.

The valve member 2 is provided with a pin 24 that extends into an opening 25 in the boss 16 and contacts a head 26 on a pin 27 which is slidably mounted in a bushing 28 that is threaded 40 in the boss 16. The outer end of the bushing 28 is provided with a packing gland 29 that is threaded on a shank 30 extending from the outer end thereof.

45 The outer end of the pin 27 engages a lever 31 that is pivotally mounted between ears 32 on the lower side of the valve body by a pin 33 and the upper end of this lever extends upward so that it may be conveniently engaged by the thumb of 50 a hand on the handle 3 and it will be noted that as the upper end of the lever is pressed inward it will move the pin 27 inward and this will move the valve member 2 away from the seat 19 through the pin 24 thereby opening the passage 55 and permitting steam to pass from the interior of the valve body through the passage 21, the opening 17, the valve seat 19, the opening 25, and the passage 23 to the nozzle 7; and it will be noted that as soon as the lever 31 is released 60 the spring 20 will force the valve member against the seat and close the passage thereby instantly shutting off the steam. The lever 31 is provided with a point 34 which engages the surface 65 of the nipple 6, as shown in Figure 2, to limit the outward movement thereof, and the spring 20 will hold the lever in this position, with the valve closed.

70 The handle 3 is attached to the upper end of a U-shaped frame 35 and the frame is provided with a base 36 that is attached to lugs 37 and 38 on the upper side of the valve body by the bolts 39 and 40 as shown. It will be understood, however, that the handle may be of any other 75 type or design, may be arranged in any man-

ner and may be attached to the valve by any means.

It will be understood that changes may be made in the construction without departing from the spirit of the invention. One of which changes 5 may be in the use of other means by which the device may be held by hand, another may be in the use of other means for connecting the live steam to the device, another may be in the use of other means for taking care of the return or condensation, and still another may be in the use of other means for operating the valve.

The construction will be readily understood from the foregoing description. In use the valve 15 may be provided as shown in Figure 1 and may be connected to live steam through the nipple 8 with the nipple 10 connected to a return, and with a nozzle 7 arranged as shown. The handle 3 may be gripped in the right hand and held so that the thumb may readily engage the upper end of the lever 31. When it is desired to spray steam the lever may be pressed so that the valve will open and steam will pass through the device as hereinbefore described. And it 20 will be noted that the flow of steam may be readily controlled by the lever and the steam may be instantly shut off and also instantly turned on, and when the steam is turned off condensation does not accumulate in the valve body as 25 all condensation passes immediately into the return through the connection into which the nipple 10 is connected. The device may therefore be readily used without danger of any water whatever being sprayed or discharged through 30 the nozzle and the valve may be opened instantly the full amount, or to any amount desired so that any amount of steam may readily be sprayed.

Having thus fully described the invention, what I claim as new, and desire to secure by Letters Patent is:

1. A dry steam spraying device comprising a valve body, a live steam connection extending into the upper part thereof, a nozzle extending from one end thereof, a valve between said live steam connection and said nozzle, a pocket extending downward from said live steam connection, a return connection from the lower end of said pocket, a handle extending upward on the upper side of said valve body, and means operating said valve, said valve operating means extending upward to a position adjacent said handle.

2. A device as described in claim 1 in which the valve is horizontally positioned and extends 45 transversely of said valve body.

3. A spraying device for dry steam and the like comprising a casing having a straight passage in the upper part thereof with a pocket extending downward from said passage, a valve in said 50 passage beyond the pocket, means supplying live steam to said passage, a steam return connection to said pocket, an outlet connection on the other side of said valve and means readily opening and closing said valve.

4. A device as described in claim 3 having a handle.

5. A device as described in claim 3 having means resiliently holding the valve in the closed position.

6. A device as described in claim 3 having a handle, means resiliently holding the valve in a closed position, and in which said valve operating means comprises a lever positioned to engage a stem extending from said valve and also adapt- 70 75

- ed to be engaged by a thumb of a hand on said handle.
7. A device as described in claim 3 in which the casing is of a triangular shape with the valve substantially positioned in the vertex thereof.
- 5 8. A device as described in claim 3 in which the return connection is positioned at the extreme bottom of said pocket and adapted to remove all condensation.
- 10 9. A device as described in claim 3 in which the respective parts are so positioned that when the valve is closed a circulation of steam may pass through said casing and out of said return connection.
- 15 10. A dry steam spraying device comprising a casing having a live steam passage therethrough, means closing the outer end of said passage, and a return connection into which the steam passes continuously when the outer end of the passage 20 is closed.
11. A device as described in claim 10 having a condensation pocket into which said return connection is connected.
- 25 12. A device as described in claim 10 having a nozzle extending from said live steam passage and beyond the means closing said passage.
13. A device as described in claim 10 having a handle by which it may readily be held by hand.
14. A device as described in claim 10 having a handle by which it may readily be held by hand and also having a lever with the end positioned adjacent said handle, said lever adapted to operate the means closing said live steam passage. 5
15. A device as described in claim 10 having a nozzle extending from said passage closing means and in which the closing means is positioned at the extreme end of said passage and adjacent said nozzle. 10
16. A device as described in claim 10 having a nozzle extending from said passage closing means and in which the closing means is positioned at the extreme end of said passage and adjacent said nozzle and also in which said closing means 15 may readily be adjusted to supply any amount of steam desired.
17. A device as described in claim 10 having a nozzle extending from said passage closing means and in which the closing means is positioned at the extreme end of said passage and adjacent said nozzle and also in which said closing means 20 may readily be adjusted to permit the passage of any amount of steam desired and completely 25 closed instantly.
